United States Patent Office

Des. 198,534
Patented June 30, 1964

198,534

TERRARIUM

Arthur F. Klingberg, Elmwood Park, Ill., assignor to Beco Products Corporation, Chicago, Ill., a corporation of Illinois

Filed Jan. 2, 1964, Ser. No. 78,015

Term of patent 14 years

(Cl. D35—3)

FIG. 1 is a top plan view of a terrarium showing my new design;

FIG. 2 is a side elevation thereof; and

FIG. 3 is an end elevation thereof.

I claim:

The ornamental design for a terrarium, as shown.
